UNITED STATES PATENT OFFICE.

AUGUSTIN J. CHEVRETTE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

LOOM.

1,126,391.

Specification of Letters Patent.

Patented Jan. 26, 1915.

Application filed May 20, 1914. Serial No. 839,861.

To all whom it may concern:

Be it known that I, AUGUSTIN J. CHEVRETTE, a citizen of the United States, residing at Worcester, in the county of Worcester and State of Massachusetts, have invented a new and useful Loom, of which the following is a specification.

This invention relates to a loom and particularly to an improved device for checking the shuttle and holding it within the shuttle box.

It is the object of my invention to provide an improved construction in devices of this character, combining efficiency of operation with simplicity of parts and economy of manufacture.

With this object in view, my invention consists in certain devices, arrangements and combinations of parts which will be herein-after described and more particularly pointed out in the appended claims.

A preferred form of the invention is shown in the drawings, in which—

Figure 1 is a top plan view of a portion 25 of a loom with my improved shuttle checking and binding device attached thereto; Fig. 2 is a view similar to Fig. 1 but showing the parts in a different position; Fig. 3 is a detail view showing the method of operating the binder release from the crank arm, and Fig. 4 is a partial sectional view taken substantially along the line 4—4 of Fig. 1.

Referring to the drawings, I have shown 35 in Fig. 1 a portion of the lay 10 of a loom having the usual back binder plate 11 secured thereon. The crank arm 12 is connected in the usual way to operate the lay.

My improved construction relates particularly to the front binder 13 and the means for operating the same. The binder 13 has its left hand end, as viewed in Fig. 1, positioned in a slot in the upstanding portion of a casting 13^a secured to the lay.

45 An upwardly extending binder finger 13^b presses against the end of the binder 13, the binder being thereby retained within the slot in the casting 13^a. The binder finger 13^b is connected in the usual way to operate 50 a dagger or other safety device for stopping the lay when the shuttle fails to box properly. Near its right hand end, the binder 13 is provided with a ball-and-socket connection 14 by which it is adjustably secured 55 to the arm 15^a of a curved lever 15 pivot-

ally mounted at 16 upon a bracket secured to the lay 10. The stud 17 which constitutes a part of the ball-and-socket connection 14 is threaded and is provided with nuts 18 by which the relation of the binder to the 60 arm 15^a may be varied. The other end of the lever 15 comprises a substantially semi-circular arm 15^b, formed integral with the arm 15^a, the outer extremity by the arm 15^b being positioned at the rear of the lay. The 65 arm 15^b is connected by toggle links 20 and 21 to a stud 22 fixed in the lay. The link 21 is provided with a rearwardly extending arm 23 positioned to contact with the end of a sliding rod 24.

The rod 24 is pivotally connected at one end to a bell crank 25 mounted on a stud 26 in a bracket 27 secured to the rear side of the lay. The other end of the rod 24 slides freely in a bearing 28 fixed to the lay. A coiled tension spring 29 has its opposite ends connected respectively to the bearing 28 and to the arm 23, the tension of the spring acting at all times to draw the arm 23 toward the bearing 28.

The bell crank 25 has a rod 30 secured thereto which extends into the path of a flanged plate 31 which is bolted to the upper side of the crank arm 12. Reference to Fig. 3 will show that, as the crank pin rises after 80 the crank has passed its forward center, the flanged plate 31 will move forward relatively to the lay from the position shown in Fig. 1 to that shown in Fig. 2. This movement will result in swinging the bell crank 90 25 upon its pivot 26, thereby forcing the sliding rod 24 to the right. The toggle links 20 and 21 will thus be moved from the position shown in Fig. 1 to the position shown in Fig. 2 in which the toggle is broken, thereby allowing the lever 15 to swing upon its 95 pivot and permitting the binder to be moved forward, releasing the shuttle preparatory to the action of the picker thereon. As the crank pin approaches its rear center, the 100 flanged plate 31 will move rearwardly relatively to the lay thus permitting the spring 29 to slide the rod 24 to the left and causing the toggle links 20 and 21 to be moved to their locked position. In this position the 105 lever 15 will be firmly supported against the outward thrust of the binder, and the binder will thus be rendered operative to check and hold the shuttle. The exact pressure of the binder upon the shuttle may be 110

regulated by the use of the adjusting nuts 18. By the provision of the universal joint 14, the binder is permitted to angularly adjust itself with relation to the shuttle so 5 that a perfect binding contact may be secured.

Having thus described my invention it 10 will be evident that changes and modifications can be made therein without departing 15 from the spirit and scope of the invention as expressed in the claims, and I do not wish to be limited to the specific details herein disclosed, but

What I do claim is:—

- 15 1. In a loom, in combination, a lay, operating means therefor, a binder on said lay, a lever mounted on said lay and pivotally connected to said binder, means to positively lock said lever against the outward pressure of said binder, and connections from said operating means to said locking means, whereby said locking means is alternately moved into and out of locking position.
- 20 2. In a loom, in combination, a lever, a binder pivotally connected to said lever, a toggle for moving and locking said lever and said binder in operative position, and means for breaking said toggle.
- 25

3. In a loom, in combination, a lever 30 pivotally mounted upon the lay, a binder adjustably connected by a universal joint to one end of said lever, a toggle connected to the other end of said lever and to the lay, yielding means for closing said toggle, and 35 positive means for breaking said toggle.

4. In a loom, in combination, a crank arm, a binder, a lever adjustably connected to said binder, a substantially semi-circular arm integral with said lever, toggle links 40 pivoted to the end of said arm and to the lay, yielding means for closing said toggle, and means positively actuated by the crank arm to open said toggle.

5. In a loom, in combination, a binder, a 45 lever adjustably connected to movably support one end of said binder, said binder being free to rock in any direction on said lever, and means to periodically and positively lock said lever against outward pressure of said binder.

In testimony whereof I have hereunto set my hand, in the presence of two subscribing witnesses.

AUGUSTIN J. CHEVRETTE.
